W. E. WOODARD,
DRAFT CONNECTION.
APPLICATION FILED JUNE 27, 1921.

1,426,436.

Patented Aug. 22, 1922.

UNITED STATES PATENT OFFICE.

WILLIAM E. WOODARD, OF FOREST HILLS, NEW YORK, ASSIGNOR TO FRANKLIN
RAILWAY SUPPLY COMPANY, A CORPORATION OF DELAWARE.

DRAFT CONNECTION.

1,426,436.

Specification of Letters Patent. Patented Aug. 22, 1922.

Application filed June 27, 1921. Serial No. 480,539.

To all whom it may concern:

Be it known that I, WILLIAM E. WOODARD, a citizen of the United States, residing at Forest Hills, in the county of Queens and 5 State of New York, have invented certain new and useful Improvements in Draft Connections, of which the following is a specification.

My invention relates to draft connections, 10 and especially to draft connections of the type commonly used between railway locomotives and their tenders wherein a plurality of draft bars are employed. In such draft connections as usually constructed, 15 there is a main "service" draft bar which normally constitutes the active connection and takes the entire tractive load, and a safety draft bar which comes into action and takes the load only in emergencies, when 20 the service draft bar has failed. A draft connection of this general type, (commonly known as the "Unit safety bar"), is shown in United States Patent No. 1,257,859, granted February 26, 1918, to Charles L. 25 Heisler.

I aim to obviate a serious drawback of double bar draft connections heretofore used: namely, a liability of the draft bars 30 to transverse bending stresses and strains during service, encountered when the locomotive and tender undergo considerable angular displacement, vertically, relatively to one another,—as in passing over a sharp hump or crest in the track, or a sharp hollow. 35 I also aim to minimize the vertical space required by the draft connection, especially on the locomotive so that it shall not interfere with other parts of the locomotive structure and equipment. This is a matter 40 of great practical importance on locomotives equipped with the "booster" shown in United States Patent No. 1,339,395, granted May 11, 1920, to Howard L. Inggersoll. I further aim, at the same time, to render the 45 coupling and uncoupling of locomotive and tender quite easy, convenient, safe, and expeditious.

How these and other advantages can be 50 realized through my invention will appear from my description hereinafter of the best form of embodiment at present known to me.

In the drawings, Fig. 1 shows a vertical

longitudinal section through a locomotive and tender draft connection conveniently embodying my invention.

Fig. 2 is a plan view of the draft bars, with certain accessory parts in horizontal section as indicated by the line 2—2 in Fig. 1.

The locomotive and tender end frames 5 and 6 are shown as provided with the usual buffer structures 7 and 8. On the tender frame 6 is a draft head 9 having a pair of draft bar pockets (or a double pocket) 10, 65 11, which may be of the usual unit safety bar construction. On the locomotive frame 5 is a draft head 12 having a single draft bar pocket 14 which resembles the usual construction in its relation to the rest of the 70 frame, except that it occupies considerably less space vertically and does not extend downward so far. The service draft bar 15 is uppermost, with one apertured portion 16 in the upper tender pocket 10 and its other 75 apertured end portion 17 in the locomotive pocket 14. The safety or emergency draft bar 20 is below the service bar 15, with one apertured end portion 21 in the lower tender pocket 11 and its other apertured end portion 22 in the locomotive pocket 14, directly 80 beneath the bar end 17. The draw bar ends 16 and 21 are adapted to be connected to the tender draw head 9 at either side of the transverse horizontal web 23 separating the 85 pockets 10 and 11, by means of the usual removable draw pin 24, secured in place in the usual way.

The apertured end 22 of the safety bar 20 embraces a fixed upwardly extending hub 90 or boss 25 on the interior of the pocket 14. As shown, the service bar end 17 does not rest directly on the safety bar end 22, but on the boss 25. This boss 25 is hollow, and the service bar end 17 is connected to the 95 draw head 12 within the pocket 14 by means of a removable draw pin 26 embraced by said end 17 and extending into said box 25. As shown, the head 27 of the draw pin 26 is at its lower end, and the draw pin extends clear through the boss 25 and the bar end 17, as well as the bottom and top pocket walls 28 and 29.

The end apertures of the safety bar 20 allow considerably more lost motion or relative movement between the locomotive and

tender draw heads 9 and 12 than do those of the service bar 15, so that the safety bar cannot take any tractive effort unless the service bar breaks. Potentially, nevertheless, 5 the safety bar 20 is virtually connected to the draw heads 9 and 12 all the time. The draw bar end 17 serves, it will be seen, to maintain the safety bar end 22 in proper position with reference to the boss 25. The 10 safety bar 20 is slightly bent at 31 and 32 so as to bring the end portion 22 substantially closer to the end portion 17 of bar 15 which minimizes the possibility of strains as the locomotive and tender ride over a 15 sharp crest or a sharp depression in the track. The bending also allows the end portions 21 and 22 to lie substantially horizontal in the pockets 11 and 14, notwithstanding their difference in level.

20 It will readily be seen that the vertical dimension of the locomotive draw head and pocket structure 12, 14 is greatly reduced as compared with a construction like that of the tender head and pocket structure 9, 25 10, 11. This reduction is such as to allow plenty of room beneath the structure 12, 14 for a locomotive booster and its accessories. Not only is this economy of space attained without sacrifice of clearance above 30 and below the draw bar ends, but it even permits increased clearances about these ends, so as to obviate all risk of either bar being bent and so weakened or broken by vertical relative displacement or relative angular variation of locomotive and tender.

35 These advantages are attained without sacrifice of strength in any way, since the unsupported "span" length of the draw pin 26 between the boss 25 that surrounds this pin and the pocket wall 27 is no greater than the span lengths of the pin 24 at either side of the web or diaphragm 23. As shown, all the draw head holes for the draw pins 24 and 26 have steel liners 33 which may be 40 accurately finished, fitted, centered, and aligned to give the proper distribution of support and loading for these pins.

45 A very important point in regard to draft connections is the matter of coupling and uncoupling. With the combination of drawheads hereinbefore described, this offers no difficulty. In coupling, both drawbars 15 and 20 can be inserted and secured in the locomotive pocket 14, as shown, and 50 the tender with its double pocket 10, 11 then advanced upon their ends 16, 21 in the usual way; while in uncoupling, the mere withdrawal of the tender drawpin 24 leaves the drawbars 15, 20 free to draw out of the 55 tender pocket 10, 11. For such case of coupling and uncoupling, however, it must be possible to effect concurrent insertion or connection (and vice-versa) of both drawbars at one, at least, of the draftheads interconnected by them, "concurrent," that

is, in a sense equivalent or analogous to the securing or connecting up of both drawbars 15 and 20 at the tender draft head 9 that results when the pin 24 is slipped in, as distinguished from the necessity that 70 exists of inserting and securing the draw bar 20 at the head 12 before the drawbar 15 can be inserted or attached. If both of the interconnected draftheads were like the head 12 shown, it would be impossible to 75 couple them up or uncouple them with any degree of convenience or quickness.

The boss or hub 25, it will be observed, is higher than the thickness of the bar end 22 which embraces it, and the bar end 17 is thus 80 supported solely by the boss, without contact with the bar end 22. This avoids needless rubbing, jarring, banging and rattling of the bar ends 17 and 22 together as they rock in the pocket 14 with relative vertical movement of the tender and locomotive drawheads 9 and 12.

I claim:

1. In a locomotive and tender connection the combination of a pair of draw bar pockets on the tender one above the other, a single draw bar pocket on the locomotive, a hub extending upwardly from the lower portion of the locomotive pocket, a draw bar extending at one end into the upper pocket on the 90 tender and at the other end into the pocket on the locomotive, the locomotive end being adapted to rest upon said hub, a safety bar extending at one end into the lower pocket on the tender, said safety bar being bent 95 upwardly from said end so as to enter the pocket on the locomotive at the other end and being adapted at the locomotive end to embrace the hub, a pin on the tender for the ends of both bars and a pin on the locomotive for the end of the draw bar only.

2. The combination with locomotive and tender frames, one of which has a single draw bar pocket and the other a double pocket, of a draw bar and pins, and a safety 100 bar shaped to have an end lie in the single pocket with an end of the draw bar and an end lie in the second aperture of the double pocket, whereby the safety bar is attachable and detachable from one of the frames 110 concurrently with the draw bar by removal of the respective pin.

3. The combination with locomotive and tender frames, one of which has a single draw bar pocket and the other a double 120 pocket, of a draw bar and pins, and a safety bar shaped to have an end lie in the single pocket with an end of the draw bar and an end lie in the second aperture of the double pocket, whereby the safety bar is attachable 125 and detachable from one of the frames concurrently with the draw bar by removal of the respective pin, said single draw bar pocket having a hub and the safety bar having an eye fitting said hub.

4. The combination with locomotive and tender frames, one of which has a single permanent draw bar pocket and the other a double permanent pocket, of a draw bar and 5 pins, and a safety bar shaped to have an end lie in the single pocket with an end of the draw bar and an end lie in the second aperture of the double pocket, whereby the safety bar is attachable and detachable from one of the frames concurrently with the draw bar by removal of the respective pin.
- In testimony whereof, I have hereunto signed my name.

WILLIAM E. WOODARD.
